US00D951916S

(12) **United States Design Patent** (10) **Patent No.:** **US D951,916 S**
(45) **Date of Patent:** **** May 17, 2022**

(54) **EARPHONE**

(71) Applicant: **Shenzhen Ginto E-Commerce Co., Limited**, Shenzhen (CN)

(72) Inventor: **Yong Yang**, Shenzhen (CN)

(73) Assignee: **SHENZHEN GINTO E-COMMERCE CO., LIMITED**, Shenzhen (CN)

(**) Term: **15 Years**

(21) Appl. No.: **29/760,298**

(22) Filed: **Nov. 30, 2020**

(30) **Foreign Application Priority Data**

Nov. 19, 2020 (CN) 202030703268.8

(51) **LOC (13) Cl.** **14-01**

(52) **U.S. Cl.**

USPC **D14/223**

(57) **CLAIM**

The ornamental design for an earphone, as shown and described.

DESCRIPTION

FIG. 1 is a perspective view of an earphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the earphone that form no part of the claimed design.

1 Claim, 8 Drawing Sheets
